UNITED STATES PATENT OFFICE.

JOHN H. PILLINGS, OF DAYTON, OHIO, ASSIGNOR OF ONE-HALF TO BENJAMIN H. NOYES, OF DAYTON, OHIO.

SELECTIVE OPERATING MECHANISM.

1,208,641.

Specification of Letters Patent. Patented Dec. 12, 1916.

Application filed July 13, 1914. Serial No. 850,550.

To all whom it may concern:

Be it known that I, JOHN H. PILLINGS, a citizen of the United States, residing at Dayton, in the county of Montgomery and State of Ohio, have invented certain new and useful Improvements in Selective Operating Mechanism, of which the following is a specification, reference being had therein to the accompanying drawing.

This invention relates to selective operating mechanism, and it is designed more particularly for use in connection with typewriters, but is capable of application to devices of various kinds having a plurality of parts to be selectively operated.

The present invention is a modification of, and constitutes in some respects an improvement on, devices for similar purposes shown and described in applications for patents, filed by me Sept. 29th, 1913, Ser. No. 792,368, and October 10th, 1913, Ser. No. 794,775.

The object of this invention is to simplify the construction and operation of the machine and thereby reduce the weight of the machine, the cost of production and the cost of maintenance.

To this end it is a further object of the invention to provide pneumatically controlled selective mechanism for establishing a positive connection between a driven actuating member and a selected part to be operated.

In the accompanying drawings Figure 1 is a side elevation of the mechanism embodying my invention; Fig. 2 is a longitudinal sectional view taken through the upper portion of the device and showing the connection with the operative parts of the typewriter; Fig. 3 is a top plan view of the mechanism shown in Fig. 2; Fig. 4 is a rear elevation, partly in section, of the pneumatic selective mechanism; Fig. 5 is a detail view of the carriage return mechanism; Fig. 6 is a plan view of the tabulating attachment; Fig. 7 is a side elevation of the same; and Fig. 8 is a detail view of the trip for the carriage return mechanism.

In these drawings I have illustrated one embodiment of my invention and have shown the same as mounted on a main frame 1, which is preferably in the form of a cabinet, which incloses the operative parts of the mechanism. Mounted upon this main frame is a typewriter 2, of ordinary con-

struction, or any other device which is to be operated. This typewriter is provided with the usual type bars 4 which constitute the parts to be operated, and these type bars are connected with the key bars 5 in the usual manner.

In carrying out my invention I provide an actuating member which is positively driven, preferably continuously, and is adapted to be connected with any one of the operable parts, or type bars, of the typewriter. In connection with this actuating member I provide a pneumatically controlled selective mechanism to operatively connect the actuating member with a selected one of said operable parts. Preferably the selective mechanism comprises a series of selecting devices adapted to be moved into operative relation with the actuating member to establish the desired connection. These selecting devices are all connected, in the present form of the invention, with suction devices which serve to hold said selecting devices in their inoperative positions. This suction is preferably controlled by a perforated web of paper, or the like, moving over an apertured bar. When one of the apertures in the web of paper is brought into alinement with one of the apertures in the bar, the suction which is holding a particular one of said selecting devices in its inoperative position is relieved and this device is permitted to move into its operative position with relation to the actuating member, thereby establishing a positive connection between the actuating member and a selected one of the parts to be operated, this particular part to be operated corresponding to the location of the aperture in the web of paper.

This operation can be carried out by various mechanisms, and it will be understood that the mechanism which I have illustrated, and will hereinafter describe, has been chosen for the purpose of illustration only. In this mechanism the actuating member comprises a single bar 6 extending transversely of the machine, mounted at its ends in suitable guideways 7 and connected at its ends with two connecting rods 8, to the upper ends of which are secured eccentric straps 9. These straps extend about eccentricities 10 rigidly secured to a shaft 11 near the opposite sides of the main frame 1, which shaft may be rotated in any suitable manner.

and, when rotated, will impart a vertical reciprocating movement to the actuating member or bar 6. In the present instance the shaft 11 is driven from a motor 26 by means of a belt 36, extending about a pulley 37 on one end of the shaft 11. Means are provided for establishing operative connections between the actuating member 6 and the several parts to be operated, to cause these parts to be operated by the reciprocation of the bar. As here shown these connections are established by means of connecting devices, which, in the present instance, are in the form of levers 12 fulcrumed between their ends upon a shaft or rod 13, mounted in brackets 14, carried by the main frame. The connecting members or levers are fulcrumed at a point nearer the rear ends than the front ends thereof, and the front ends are connected by means of rods or links 15 with the key bars 5. These links may be of any suitable connection, but are preferably of the construction and arrangement shown in the above mentioned applications and need not be here particularly described. Suffice it to say that the arrangement is such that the key bar is caused to move downward with the forward end of the connecting member with which it is associated and that the connecting member is automatically returned to its normal or elevated position, thereby permitting the key bar to return to its normal position. The rear ends of the several connecting members 12 are arranged directly above the actuating member 6 but are spaced away from this member such a distance that they will not be engaged thereby, when the actuating member is reciprocated. In order to establish an operative connection between the actuating bar 6 and a selected one of the connecting members 12, I have provided a pneumatically controlled selective mechanism, comprising a series of selecting devices or fingers 16 mounted for lengthwise movement to bring the same into operative relation with the actuating member, and for vertical movement to permit the same to move with the actuating member when engaged thereby. There is one of these selecting devices or fingers 16 for each of the connecting members or levers 12, and consequently, there is one selecting device for each part to be operated. As here shown, the selecting devices are in the form of flat bars arranged on their edges and supported in a slotted guide bar 17, which serves to guide them in their movements and to space them apart. The selecting devices are pivotally connected at their rear ends with plungers 18 which are slidably mounted in cylindrical guideways 19, the relation between the plungers and the selecting devices being such that when the plungers are fully seated in their guideways the selecting devices will be in their inoperative positions. But when the plungers have been moved outward for a portion of the length of the guideways the selecting devices will be brought into operative relation with the actuating member. Suitable means are provided which normally tend to move the plungers outward and, consequently, to move the selecting devices toward their outer positions. This means as here shown comprises springs 20 confined between the respective plungers and the ends 75 of their guideways. The plungers are held normally in their fully retracted positions by means of suction devices, and, in the present instance, I have shown the several guideways 19 formed in a single bar 21, extending transversely to the machine and having a longitudinal chamber 22 which constitutes a vacuum chamber and is connected with the several cylindrical guideways by means of apertures or conduits 23, and is connected by 80 means of a tube 24 with an air pump 25, of any suitable construction, which is operated from the motor 26 which drives the shaft 11. The suction created by this pump in the chamber 22 is sufficient to hold the 85 several plungers in their retracted positions against the tension of their springs.

To permit the plungers to be moved outward by their springs I have provided each of the cylindrical guideways 19 with a relief aperture or port 27 which extends through the outer wall of the bar 21. The relief ports 27 for the several cylindrical guideways are preferably arranged in alignment longitudinally of the bar 21 and the 100 adjacent face of this bar is shaped to form a bearing surface over which travels a web of paper 28, or other suitable material, which serves when in contact with the bearing surface of the bar to close the apertures 105 and permit the suction in the chamber 22 to hold the plungers seated. This web of paper is provided with apertures so arranged that as the web is advanced the several apertures will be brought successively 110 into alignment with the corresponding ports 27. Each aperture, thus connects a relief port with the atmosphere, relieves the suction on that particular plunger and permits the same to be operated by its spring, thereby moving the selecting device into operative relation with the actuating member 6 and establishing a positive connection between the actuating member and the particular part to be operated which corresponds with the position of the aperture in the web which has registered with the relief port 27. The apertures are formed in the web in any suitable manner but are so arranged that they will register successively 115 with the relief ports 27 and will operate said relief ports in such a sequence as to cause the parts to be operated or type bars to be actuated in the order necessary to produce the desired results. The web of paper 28 may 120

130

be supported and actuated in any suitable manner, and, in the present instance, I have shown it as passing about a feed roller 29 which supports the same above the bar 21 and is provided with teeth 30 which register with openings 31 along the edges of the web of paper and serve to feed the same forward and to hold the same against lateral displacement. The roller 29 may be driven in any suitable manner, but, in the present instance, it is mounted on a shaft 32 and is driven from a shaft 33 by worm gearing 34, the shaft 33 being geared to the shaft 11. A guide roller 35 is preferably provided on that side of the bar 21 opposite the roller 29 and the two rollers are so arranged as to hold the web of paper firmly against the bearing surface of the guide bar, thereby causing it to close the relief ports. The suction through the relief ports will also assist in holding the paper firmly in engagement with the bar and will cause the same to effectually close the ports.

I have also provided means to lock the several plungers against outward movement when the suction thereon is relieved. To accomplish this each of the selecting devices is provided in its lower edge with a notch 38 adapted to receive a locking member or plate 39, which is mounted on a rod 40, extending transversely to the several selecting devices and rotatably supported by the main frame. Secured to the rod 40 is an arm 41 to which is secured the upper end of a piston rod 42, the lower end of which is connected with a piston 43, mounted in a cylinder 44 and held normally in its elevated position by a spring 45. This cylinder is connected by means of a tube 46 with the suction device 25 so that when the mechanism is in operation suction will be exerted on the piston 43 and the tension of the spring 45 is such that the spring will be compressed by the suction, and the locking plate 39 moved into and held in its inoperative position. Preferably the spring 45 has a greater tension than the springs 20 of the plungers, and consequently, when the suction is decreased the spring 45 will actuate its piston, and, consequently, the locking device 39 before the springs 20 will actuate their plungers. Thus the locking device operates before the plungers are released and there is no possibility of these plungers being displaced by the expansion of their springs after the motor has stopped. Likewise, when the apparatus is started the suction, as it gradually increases, will first become sufficient to retain the plungers in their retracted positions, and subsequently, will actuate the piston 43 to move the locking device into its inoperative position.

I have found it desirable, however, to provide a positive control for the locking cylinder 44. To this end I have provided the cylinder 44 with a positively controlled

valve, which, in the present form, comprises a supplemental cylinder 62 in open communication with the cylinder 44 of the locking device, and having a valve member 63 to control its communication with the atmosphere. When this valve is opened the pressure in the cylinder is instantly relieved and the piston is permitted to move down more quickly than would be the case if the relief was through the tube 46. When this valve is closed the suction acts on the piston 43 the same as it would in the absence of the valve. The valve may be operated in any suitable manner, but preferably it is connected with the key, on the key board, which controls the operation of the mechanism. This key may be connected with a switch in substantially the manner as shown and described in my application 794,775, above mentioned, and is further connected with the valve 63 by a system of levers and rods as indicated at 66, the arrangement being such that when the starting key is actuated to start the motor the valve 63 will be seated, and when the key is actuated to break the circuit and stop the motor the valve will be unseated and the pressure in the locking cylinder relieved.

The carriage return is accomplished in somewhat the same manner as it is in the applications above mentioned, but the driving shaft is arranged lengthwise of the machine on the outside of the frame, and constitutes in the present arrangement, the same shaft, 33, that drives the roller 29, and has rigidly secured thereto a clutch member 47. Mounted in bearings 48 is a short shaft 49 arranged in alignment with the shaft 33, and having rigidly secured to that end thereof adjacent to the clutch member 47, a clutch member 50 adapted to coöperate with the clutch member 47, to connect together the shafts 33 and 49. The shaft 49 has at one end a grooved collar 51 to receive the ends of a yoke 52, which is secured to the lower end of a vertical shaft 53, journaled in bearings 54 and having at its upper end a rock arm 55. Mounted on the shaft 53 is a spring 56 which tends to move the shaft 49 in a direction to bring the two clutch members into operative relation and thus connect the two shafts. A suitable locking device is provided to retain the clutch members in their disconnected positions, and, as here shown, this device comprises a latch consisting of a finger 57 pivotally mounted on the frame near the lower bearing 54 and adapted to engage a keeper 58 connected with the shaft, and, in the present instance, secured to the lower arm of the yoke 52. Connected with the latch arm 57 is a second arm 59 to which is connected a link 60 corresponding to the links 15 which connect the actuating device with the key bars. This link is connected with the actuating device in the same man-

ner as the other links, and the perforated web is provided with a perforation for the end of each line, which causes the latch to be actuated to release the shaft 49 and permit the clutch members to be moved into operative engagement by the spring 56. Mounted on the shaft 49 and rotating therewith is a drum 61 upon which is wound a tape 61^a which is connected at its upper end 10 with the typewriter carriage. Consequently, as soon as the latch is released the clutch members are positively engaged, the tape wound upon the drum and the carriage returned to its initial position. As the carriage 15 approaches its initial position a stop mounted thereon, as shown at 55^a, engages the rock arm 55 of the shaft 53, moves the shaft 49 in a direction to disconnect the clutch members and to again cause the latch 20 member 57, which is spring-actuated, to engage its keeper and lock the clutch members in their disconnected positions. Connected with the drum 61 is a weight 67 which tends to rotate the drum and to wind up the tape 25 when the clutch members are disconnected, and thus to take up the slack in the tape.

In order to use the automatic operating mechanism in connection with a tabulator on a typewriting machine, it is necessary 30 that a special device be provided to hold the tabulator key down until the carriage has moved the desired distance. When operated by hand this key is naturally held down long enough to permit of the movement of the carriage, but the automatic operation is so rapid that it is necessary to provide this auxiliary device. In Figs. 6 and 7 the tabulator frame is shown at 68 and the tripping stops at 69. These parts 40 are of ordinary construction and operation and need not be described in detail. In connection with these devices I have provided a bracket 70 on which is mounted an arm 71 extending through the tabulator frame 45 and having mounted thereon a spring-actuated dog 72 which normally bears against the side of a plate or bar 73 secured to the tabulator frame. When the tabulator frame is operated, this dog engages back of 50 the plate 73 and thus locks the plate and the frame in their retracted positions until the carriage has completed its movement.

The operation of the mechanism will be 55 readily understood from the description of the operation of the several parts thereof, and it will be apparent that when a record has been made on a web of paper in any suitable manner and this web mounted in the machine, that the type bars will be 60 caused to move in the proper sequence to typewrite the matter which has been placed upon the paper record, and that this matter can be rewritten as often as is desired. It is 65 possible to quickly remove one record and substitute another by simply removing the

roller 32, it being detachably connected with its trunnions. The record which has been removed can be rolled into a small compass and filed where it will be readily accessible when it is again desired to typewrite the 70 same matter. It will be noted that the mechanism is very simple in its construction and in its operation, that it comprises a comparatively small number of parts and that the operation of the type bars is accomplished by a positive connection with the actuating member, the pneumatic mechanism serving only to establish a connection between the actuating member and the type bars. This not only makes it possible to 80 operate the machine with a small suction apparatus, but it does away with the uncertainty of a suction-operated actuating device.

While I have shown and described one 85 embodiment of my invention, it will be understood that this has been chosen for the purpose of illustration only, and that I do not desire to be limited to the details thereof, as obvious modifications will occur to one 90 skilled in the art.

Having thus fully described my invention, what I claim as new and desire to secure by Letters Patent, is:—

1. In an operating mechanism of the character described, the combination, with an actuating device, and a plurality of parts to be actuated, said parts being normally disconnected from said actuating device, of selecting devices movable into positions to 100 connect said actuating device with selected parts to be operated, a series of pneumatic operating devices for said selecting devices comprising air chambers, movable members operatively connected with the respective 105 selecting devices, an air pump connected with said chambers and acting on said movable members to move the same in one direction, and means to move said movable members in the other direction, said chambers 110 having individual controlling ports leading directly to the atmosphere and adapted to be opened and closed to control the operation of the selecting device.

2. In an operating mechanism of the character described, the combination with an actuating member and a plurality of parts to be actuated, said parts being normally disconnected from said actuating member, of selecting devices movable into positions 120 to connect said actuating member with selected parts to be operated, a series of cylinders arranged adjacent to said selecting devices, plungers mounted in said cylinders and connected with the respective selecting devices, springs tending to move said plungers in one direction and an air pump connected with said cylinders to move said plungers in the other direction, each cylinder 125 having a relief port adapted to be 130

opened and closed to control the action of said air pump on the piston in that cylinder.

3. In an operating mechanism of the character described, the combination with an actuating member and a plurality of parts to be actuated, said parts being normally disconnected from said actuating member, of selective mechanism including a suction apparatus, a plurality of cylinders, each connected with the suction apparatus and each having a relief port, plungers mounted in the several cylinders, selecting devices connected with the respective plungers and adapted to establish an operative connection between said actuating device and the respective parts to be operated, springs to move said plungers in one direction and means to control said relief ports.

4. In an operating mechanism of the character described, the combination with an actuating member and a plurality of parts to be actuated, said parts being normally disconnected from said actuating member, of selective mechanism comprising a bar arranged adjacent to said actuating member and having a series of cylinders formed therein and also having a longitudinal chamber connected with each of said cylinders, each of said cylinders having a relief port, plungers mounted in the several cylinders and selecting devices connected with the several plungers and movable to establish operative connections between said actuating member and the respective parts to be actuated.

5. In an operating mechanism of the character described, the combination with an actuating member and a plurality of parts to be actuated, said parts being normally disconnected from said actuating member, of selective mechanism comprising a bar arranged adjacent to said actuating member and having a series of cylinders formed therein and also having a chamber connected with each of said cylinders, each of said cylinders having a relief port, plungers mounted in the several cylinders and selecting devices connected with the several plungers and movable to establish operative connections between said actuating member and the respective parts to be actuated, and means to movably support a perforated web of paper in operative relation to said relief ports.

6. An operating mechanism of the character described, comprising an actuating device, selecting devices to operatively connect said actuating device with a selected one of a plurality of parts to be operated, means to move the respective selecting devices in a direction to establish such a connection, and a suction apparatus connected with the respective selecting devices and normally acting thereon to move the same in the other direction and to interrupt such a connec-

tion, said suction apparatus comprising a separate air chamber for each selecting device, each air chamber having a relief port leading directly to the atmosphere and adapted to be opened and closed to control the movement of its selecting device.

7. An operating mechanism of the character described, comprising an actuating device, selecting devices to operatively connect said actuating device with a selected one of a plurality of parts to be operated, a series of pneumatic operating devices for said selecting devices comprising air chambers, movable members operatively connected with the respective selecting devices, suction apparatus connected with said chambers and acting on said movable members to move the same in one direction, means to move said movable members in the other direction when the suction thereon is relieved, said air chamber having individual relief ports leading directly to the atmosphere and arranged to be normally closed by a perforated web passing over the same, and to be opened by the perforations in said web to relieve the suction in the respective chambers and permit said movable members to be moved in said other direction.

8. An operating mechanism of the character described, comprising an actuating member, means to impart movement to said actuating member, connecting devices movably mounted adjacent to and out of the path of said actuating member and operatively connected with the respective parts to be operated, selecting devices movable into positions to connect said actuating member with selected connecting devices, a series of cylinders arranged adjacent to said selecting devices, plungers mounted in said cylinders and connected with the respective selecting devices, springs tending to move said plungers in one direction and an air pump connected with said cylinders to move said plungers in the other direction, each cylinder having a relief port adapted to be opened and closed to control the action of said air pump on the piston in that cylinder.

9. An operating mechanism of the character described, comprising an actuating member, means to impart movement to said actuating member, connecting devices movably mounted adjacent to and out of the path of said actuating member and operatively connected with the respective parts to be operated, selecting devices movable into operative relation with said actuating member to connect the same with selected connecting devices, a bar having a series of cylinders, plungers mounted in the several cylinders and connected respectively with said selecting devices, pneumatic mechanism connected with said cylinders, each of said cylinders having a relief port and means to automatically open and close said relief ports

to control the action of said pneumatic mechanism.

10. An operating mechanism of the character described, comprising an actuating member, means to impart movement to said actuating member, connecting devices movably mounted adjacent to and out of the path of said actuating member and operatively connected with the respective parts to be operated, and selective mechanism including suction apparatus, a plurality of cylinders, each connected with the suction apparatus and each having a relief port, plungers mounted in the several cylinders, selecting devices connected with the respective plungers, springs to move said plungers in one direction and means to control said relief ports.

11. An operating mechanism of the character described, comprising an actuating member, means to impart movement to said actuating member, connecting devices movably mounted adjacent to and out of the path of said actuating member and operatively connected with the respective parts to be operated, and selective mechanism including a plurality of cylinders, a suction apparatus connected with said cylinders, each of said cylinders having a relief port adapted to be opened and closed by a perforated web of paper, the relief ports for the several cylinders being arranged in alignment, plungers mounted in the respective cylinders, and selecting devices connected with the respective plungers.

12. An operating mechanism of the character described, comprising an actuating member, means to impart movement to said actuating member, connecting devices movably mounted adjacent to and out of the path of said actuating member and operatively connected with the respective parts to be operated, selective mechanism comprising a bar extending parallel with said actuating member and having a series of cylinders formed therein, and also having a longitudinal chamber connected with each of said cylinders, each of said cylinders having a relief port, plungers mounted in the several cylinders, and selecting devices connected with the several plungers and movable into operative relation with said actuating member to connect the same with selected ones of said connecting devices.

13. An operating mechanism of the character described, comprising an actuating member, means to impart movement to said actuating member, connecting devices movably mounted adjacent to and out of the path of said actuating member and operatively connected with the respective parts to be operated, selective mechanism comprising a bar extending parallel with said actuating member and having a series of cylinders formed therein, and also having a longitudi-

dinal chamber connected with each of said cylinders, each of said cylinders having a relief port, plungers mounted in the several cylinders, and selecting devices connected with the several plungers and movable into operative relation with said actuating member to connect the same with selected ones of said connecting devices, and means to movably support a perforated web of paper in operative relation to said relief ports.

14. An operating mechanism of the character described, comprising an actuating member, means to impart movement to said actuating member, connecting devices movably mounted adjacent to and out of the path of said actuating member and operatively connected with the respective parts to be operated, and selective mechanism including a bar having a series of transverse cylinders formed therein and having a longitudinal chamber communicating with each of said cylinders, each of said cylinders having a relief port, plungers mounted in the respective cylinders, springs confined between said plungers and the walls of said cylinders to move the plungers outward, and selecting devices.

15. An operating mechanism of the character described, comprising an actuating device, selecting devices to operatively connect said actuating device with a selected one of a plurality of parts to be operated, a suction apparatus comprising a plurality of air chambers, an air conduit communicating with each of said chambers and adapted to be connected with an air pump, movable members operatively connected with the respective selecting devices and arranged to be acted upon by the suction in the respective chambers to move said selecting devices in one direction, and means to cause said selecting devices to be moved in the other direction when said suction is relieved, said air chambers having individual relief ports arranged to be opened and closed by an apertured web to control the movements of said selecting devices.

16. An operating mechanism of the character described, comprising an actuating device, selecting devices to operatively connect said actuating device with a selected one of a plurality of parts to be operated, a suction apparatus comprising a member having a plurality of air chambers and also having a longitudinally extending conduit communicating with each of said chambers and adapted for connection with an air pump, movable members operatively connected with the respective selecting devices and arranged to be acted upon by the suction in the respective chambers to move said selecting devices in one direction and means to cause said selecting devices to be moved in the other direction when said suction is relieved, individual relief ports formed in said mem-

- ber for the respective air chambers and having their outer ends arranged in the surface of said member to be opened and closed by an apertured web to control the movements of said selecting devices.
17. An operating mechanism of the character described, comprising an actuating member, devices to connect said actuating member with the respective parts to be operated, said connecting devices being normally disconnected from said actuating member, selecting devices movable into operative relation with said actuating member to establish a connection between the same and selected connecting devices, means to automatically cause the operation of said selecting devices and means to lock said selecting devices against movement into operative positions.
18. An operating mechanism of the character described, comprising an actuating member, devices to connect said actuating member with the respective parts to be operated, said connecting devices being normally disconnected from said actuating member, selecting devices movable into and out of operative relation with said actuating member to establish a connection between the same and selected connecting devices, pneumatic devices to control the movement of said selecting devices, and a pneumatically operated lock to prevent the movement of said selecting devices toward their operative positions.
19. An operating mechanism of the character described, comprising an actuating member, devices to connect said actuating member with the respective parts to be operated, said connecting devices being normally disconnected from said actuating member, selecting devices movable into and out of operative relation with said actuating member to establish a connection between the same and selected connecting devices, pneumatic devices to control the operation of said selecting devices, a lock to prevent the movement of said selecting devices toward their operative positions, and pneumatic means to control the operation of said lock in timed relation to the operation of the first-mentioned pneumatic devices.
20. An operating mechanism of the character described, comprising an actuating member, a connecting device to connect said actuating member with a part to be operated, said connecting device being normally disconnected from said actuating member, a selecting device to establish an operative connection between said actuating member and said connecting device, a cylinder, a plunger seated in said cylinder and connected with said selecting device, an air pump connected with said cylinder to create a suction therein to hold said plunger against outward movement, a lock movable into a position to prevent the outward movement of said plunger, a second cylinder, a plunger mounted in said second cylinder and connected with said lock, said second cylinder being also connected with said air pump whereby the suction in said cylinder will hold said lock in its inoperative position and said lock will be permitted to move when said suction becomes insufficient to hold said first-mentioned plunger against movement.
21. An operating mechanism of the character described, comprising an actuating member, a connecting device to connect said actuating member with a part to be operated, said connecting device being normally disconnected from said actuating member, a selecting device to establish an operative connection between said actuating member and said connecting device, suction apparatus to control the movement of said selecting device, and comprising a plunger, a lock to control the movement of said plunger, a second suction apparatus to control the movement of said lock, the last-mentioned suction apparatus being of such a character that it requires a greater suction to operate it than it required to operate the first-mentioned suction apparatus.
22. The combination with a typewriter, having a plurality of parts, an actuating member, a plurality of connecting levers pivotally supported between their ends on a common axis and connected with the respective parts to be operated, said connecting devices being normally disconnected from said actuating devices, of a plurality of selecting members mounted for movement into positions to connect selected ones of said connecting devices with said actuating member and pneumatic means to control the movement of said selecting devices, said means having a plurality of air chambers, an air pump connected with said chambers to create suction therein, members connected with said selecting devices and arranged to be acted upon by the suction within the respective chambers to move said selecting members in one direction, said air chambers having individual relief ports arranged to be controlled by a perforated web, and means for moving said selecting devices in the other direction when said suction is relieved.
23. The combination with a typewriter, having parts to be operated, an actuating member, means for imparting constant reciprocal movement to said actuating member and connecting levers connected with the respective parts to be operated and each having one end extending above and beyond the path of movement of said actuating member, of selecting members movable into the path of said actuating member to bridge the space between the same and the selected connecting lever and to cause said lever to be actuated by the movement of said actuating

8
member, a member having a plurality of air chambers and also having a longitudinal conduit communicating with each of said chambers and adapted to be connected with an air pump, relief ports formed in said member to connect the respective chambers with the atmosphere, said ports being so arranged in the surface of said member that they may be controlled by a perforated web, devices connected with the respective actuating members and arranged to be acted upon by the suction within the respective

air chambers to move said selecting members in one direction, and means to cause said selecting members to be moved in the other direction when the suction in said chambers is relieved.

In testimony whereof, I affix my signature in presence of two witnesses.

JOHN H. PILLINGS.
